Primary Examiner — Ricky Pham(74) *Attorney, Agent, or Firm* — D'Ambrosio & Menon,
PLLC; Usha Menon(57) **CLAIM**

The ornamental design for a slicer, as shown and described.

DESCRIPTION

FIG. 1 is a front view of a slicer showing my new design;
 FIG. 2 is a rear view thereof;
 FIG. 3 is a left-side view thereof;
 FIG. 4 is a right-side view thereof;
 FIG. 5 is a top view thereof;
 FIG. 6 is a bottom view thereof;
 FIG. 7 is a front perspective view thereof; and,
 FIG. 8 is a bottom perspective view thereof.

The broken lines shown in the drawings are for the purpose of illustrating portions of the slicer that form no part of the claimed design.
